United States Patent Office.

WILLIAM ROBERTSON, OF PLYMOUTH, INDIANA.

Letters Patent No. 65,608, dated June 11, 1867.

IMPROVED METHOD OF HANGING WINDOW-SASH.

The Schedule referred to in these Letters Patent and making part of the same.

TO ALL WHOM THIS MAY CONCERN:

Be it known that I, WILLIAM ROBERTSON, of Plymouth, in the county of Marshall, and State of Indiana, have invented a new and useful improvement in devices for Hanging Window-Sash; and I do hereby declare that the following is a full, clear, and exact description of the same, reference being had to the accompanying drawings and letters of reference, making a part of this specification, in which—

Figure 1 is an elevation of my invention as attached to the window-frame.

Figure 2, a perspective representation of one of the pulley-blocks with the pulley in position for use.

The nature of my invention consists in arranging a pulley-block corresponding with the thickness of the division stop, and fitting it into the top of the groove in the jamb-casing, for the purpose of providing a convenient means for hanging the upper and lower sash of windows, so that their weight will balance each other. I am well aware that sash have been hung by what is commonly known in many parts of the country as balancing cords; but as the devices used for running the cords have been of such a character as to prevent the possibility of taking the sash out of the frame in a convenient manner, as a consequence, this method is not very much in use. I claim, by means of my invention, to have obviated this difficulty by fitting the pulley-blocks into the same groove which supports the stop, by which means the stop and block can be easily removed from the frame, so as to allow the sash to be taken out for the purpose of glazing, &c.

In order to give a correct understanding of my invention, I have marked like parts with like letters, and will now give a detailed description.

A represents the common window-frame, and B C the sash, all of which are constructed in the usual manner, except the partition stops E, which are made sufficiently short at the top, as seen at D, fig. 1, to allow the pulley-blocks F to fit into the grooves shown by dotted lines G, fig. 1, and practically form a continuation of stops E. This pulley-block F is shown more clearly at fig. 2, and has the inclined slot a, for the purpose of supporting the shaft c of pulley b. The block F may be made of cast iron, and a little thicker than the stop below, so as to fit into groove G tightly, in which case it will be very durable and stay in its place.

Operation.

But little skill is required to put my device into practical use. The cords I are simply put over pulleys b in the usual manner, and attached to sash B C. When it is required to take out the sash, the stops E must first be removed, and then the blocks F can be drawn out of the grooves G, which will relieve the sash from the frame A.

Having thus fully described my device, what I claim, and desire to secure by Letters Patent of the United States, is—

The pulley-block F, when constructed and arranged substantially as and for the purpose set forth.

WILLIAM ROBERTSON.
